UNITED STATES PATENT OFFICE

CHARLES EDWARD MAY, OF BALTIMORE, MARYLAND

DESIGN FOR A BOTTLE

Application filed September 11, 1929. Serial No. 32,721. Term of patent 14 years.

To all whom it may concern:

Be it known that I, CHARLES EDWARD MAY, a citizen of the United States, residing at 702 South Wolfe St., city of Baltimore, and State of Maryland, have invented a new, original, and ornamental Design for Bottles, of which the following is a specification, reference being had to the accompanying drawing, forming part thereof.

Figure 1 is a side view in elevation of a bottle, showing my new design. Figure 2 is a side view in elevation of the same bottle after a half turn from the position shown in Figure 1.

I claim: The ornamental design for a bottle, as shown.

CHARLES EDWARD MAY.
